UNITED STATES PATENT OFFICE.

MARGARET B. GROCE, OF DALLAS, TEXAS.

DESIGN FOR A CARD-RECEIVER.

SPECIFICATION forming part of Design No. 29,817, dated December 20, 1898.

Application filed October 5, 1898. Serial No. 692,755. Term of patent 3½ years.

To all whom it may concern:

Be it known that I, MARGARET B. GROCE, a citizen of the United States, residing at Dallas, in the county of Dallas and State of Texas, have invented and produced a new and useful Design for a Card-Receiver, of which the following is a specification.

This invention is a new and useful design for a card-receiver, the essential features thereof being the peculiar shape or configuration of the box and its base or back board.

The drawings hereto annexed fully illustrate my design, in which—

Figure 1 is a perspective view of a receiver constructed in accordance with my design, and Fig. 2 is a detail sectional view.

Referring to the drawings, A represents the base or back board, the upper edge of which is pointed, as shown at B, and scalloped,

as shown at C. The side edges are serrated 20 or notched, as shown at D, and the lower edge is scalloped, as shown at E, the central scallop F being larger than the side scallop.

G represents a box having an elongated slot H in the top thereof, and I is a front panel 25 on the box.

K represents a panel produced upon the base, near the bottom of same.

Having thus described my invention, what I claim as new, and desire to secure by Letters 30 Patent of the United States, is—

The design for a card-receiver, substantially as herein shown and described.

MARGARET B. GROCE.
